METHOD AND APPARATUS FOR PRODUCING COLLAPSIBLE PAPERBOARD BODIES FOR TUBULAR CONTAINERS

Harry A. Wansker, Newtonville, Mass.

Application October 22, 1941, Serial No. 416,004

13 Claims.

(Cl. 93—36)

This invention relates to methods and apparatus for forming collapsible tubular paperboard bodies of knockdown containers of the type in which the tubular body of the container is maintained in expanded form by a rigid flat bottom inserted into the tubular body within the end portion thereof with a rigid retaining and reinforcing member or ring fitting the end of the body and clamping the body tightly against the periphery of the bottom.

When usual containers of this type are disassembled for storage or shipment the bodies are collapsed, piled one upon the other, and enclosed in a carton or bound to form a convenient package. The bottoms, covers, and rings are similarly packaged in superimposed flat positions. The paperboard bodies of containers of this type heretofore made have usually been rendered circumferentially flexible by equally spaced score lines extending longitudinally of the body which are cut through one of the surface zones of the body thereby materially weakening the wall of the body. In other instances flexibility is produced by embossing equally spaced parallel lines into the body longitudinally thereof, but in such instances the inner and outer faces of the body present parallel grooves and complementary corrugations the formation of which breaks down to a considerable extent the fibres of the body wall.

The present invention comprises a method and apparatus for use in forming a collapsible paperboard body for containers of this type in which the body is rendered pliable by impregnation of moisture from dry steam into the surface zones of the body, with thin lines extending longitudinally of the body impressed into one of the surface zones of the sheet without breaking the fibres thereof but sufficiently stretching the outer zone of the body to enable it to be bent into tubular form and to present a substantially smooth surface with only slight indentations which are hardly perceptible, thereby avoiding the weakening of the body and enabling the retaining ring most closely to fit the surface of the end of the body throughout the circumference thereof.

The present invention comprises a continuation in part of applicant's prior application Serial Number 375,238, filed January 21, 1941, and which has matured into Patent No. 2,304,615.

The method comprises broadly moving the sheet of paperboard progressively lengthwise through a surrounding circulating volume of steam thereby moistening and softening the surface zones of the sheet with moisture to render the sheet pliable, then indenting thin parallel lines into one

5 of the moistened surface zones of the sheet without breaking the fibres thereof, and sufficiently stretching the fibres of such zone to enable the sheet to be bent into tubular form when dry, cutting the sheet into sections of suitable length, and securing together the ends of the section.

In assembling the lower end of the tubular body of the sheet within the retaining ring the body is collapsed and a section thereof fitted into a

10 portion of the ring and the body then expanded to engage the remainder of the ring. In assembling usual constructions having equally spaced score lines, or equally spaced corrugations, considerable difficulty is experienced in expanding

15 the body into engagement with the ring. The present invention comprises a process of so spacing the indented lines in the surface of the body as will enable the collapsed body of the container, when a section of it is fitted within a

20 portion of the ring, to be gradually extended by a sweeping movement of the hand of the operator into the remainder of the ring without difficulty. The method comprises indenting successive sections of the moistened sheet with thin

25 parallel lines with the spacing of the lines gradually increasing in width throughout one quarter section of the sheet, then correspondingly decreasing in width throughout the next quarter section, then correspondingly increasing in width

30 throughout the next quarter section, and correspondingly decreasing in width in the last quarter section, and severing the successive sections from the sheet, and securing together the end panels of the section defined by the most narrowly spaced lines.

35 The invention also comprises the method for forming collapsible bodies of a tubular knockdown container for use with ice cream of different flavors in which the container is provided

40 with non-obliterable means for identifying the flavor or character of the contents of the container which comprises printing upon the sheet a design in suitable color to identify the contents of the container including narrowly spaced par-

45 allel lines extending longitudinally of the sheet and indenting the lines sufficiently into the surface zone of the sheet to render the sheet flexible and to prevent the indented printed portions of the lines from obliteration by abrasion of the

50 surface of the container by handling or otherwise.

A suitable apparatus for performing the methods above described is illustrated in the accompanying drawings, in which,

55 Fig. 1 is a graphic illustration of the method

of printing a sheet of paperboard, then subjecting the sheet progressively to an enclosed volume of steam, then impressing suitably spaced thin transverse parallel lines into the sheet in the manner above described and longitudinally scoring the sheet to form external end rib sections for the container;

Fig. 2 is a vertical longitudinal sectional view of an insulated steam chamber provided with means for projecting a substantially uniform current of steam in a streamlined path against the surface of the traveling sheet of material, and heating means to prevent condensation of the steam, and illustrating diagrammatically means for supplying low pressure dry steam to the steam projecting means and for supplying steam at high pressure to the heating means;

Fig. 3 is a sectional view on line 3—3 Fig. 1, viewed upwardly as indicated by the arrows in Fig. 1;

Fig. 4 is a plan view of a section of the sheet sufficient to form a container body impressed with thin lines extending transversely of the sheet, illustrating notches at the ends of the fold lines, and showing in dotted lines longitudinal scoring adjacent the edge of the sheet to permit the scored end sections to be folded upon a sheet to form external end ribs for the container body;

Fig. 5 is an enlarged sectional view of the sheet centrally broken away showing the scored edge portions in full lines and in dotted lines the position of the ribs when folded against the outer surface of the sheet; and,

Fig. 6 is a view of a collapsed container illustrating ornamentation thereon and means for identifying the contents of the container.

The mechanism for producing the successive steps in the process forming the subject matter of the invention, which is conventionally illustrated in Fig. 1, shows a roll of paperboard 1 rotatably mounted upon a suitable arbor with the free end of the sheet extending from the roll between a printing roll 2 and a complementary platen roll 3 by means of which any design, such as a design 4 (illustrated in Fig. 6) may be printed upon the sheet together with narrow lines 5 of a selected color having the same spacing as those of thin lines which are thereafter to be impressed in the sheet.

After the printing is accomplished the web preferably is continuously passed through a steam chamber 6 containing means for projecting upon one surface zone of the sheet a current of low pressure substantially dry steam of the full width of the sheet in a streamlined path in the direction of movement of the sheet to enable the surface zones of the sheet to absorb sufficient moisture to render the fibres thereof pliable and to cause the moisture to heat the ink which has been deposited upon the surface of the sheet and cause it to penetrate more deeply into the sheet and to prepare it for rapid drying as soon as the printed matter progressively emerges from the steam chamber. The sheet thereupon passes immediately from the steam chamber between a pair of complementary rolls 7 and 8 the uppermost of which is provided with suitably spaced thin blades 9 extending longitudinally of the roll for impressing thin lines into the sheet, and also may be provided at its ends with cutting disks to trim and notch the edges of the sheet, while the lower roll 8 is provided with slight depressions complementary to the blades of the cylinder 7 and adjacent or near its ends with scoring disks 10 adapted to score the sheet from beneath sufficiently to provide rib sections 11 (Fig. 4) adapted

to be folded against the outer face of the sheet, as illustrated in dotted lines Fig. 5.

Paperboard sheets suitable for bodies of tubular containers for ice cream, and other materials, are usually of laminated construction having an outer surface zone in which the fibres are more dense than those of the body of the sheet and which frequently are calendered to present a smooth surface. As a consequence, such surface zone will absorb moisture more slowly than the body of the sheet. One of the principal objects of the present invention is to subject the preferably denser surface zone of the sheet which is to be stretched when the sheet is bent to tubular form with vaporized moisture from a current of dry steam flowing in a streamlined path in the direction of movement of the sheet and which will follow the sheet as it emerges from the steam chamber sufficiently to maintain the surface zone sufficiently moist when it is engaged by the means for impressing thin lines transversely of the sheet to avoid breakage of the fibres of the surface zone, so that when the sheet is dried and thereafter bent to tubular form the container will have a continuous unbroken surface.

In the preferred form of apparatus illustrated herein the steam chamber 6 comprises a rectangular metal casing 12 which is covered preferably on the outside with a layer of insulation 13. Suitably mounted within the steam chamber 6 are metallic headers 14 and 15 which extend longitudinally of the chamber near the sides thereof and may be supported in any suitable manner (not shown). The headers may be constructed of suitable cast metal cored to provide an outer steam passage 16 for low pressure steam and a parallel inner passage 17 for heating steam of relatively higher pressure.

A plurality of metal steam delivery pipes 18 which are welded or otherwise secured at their respective ends to the headers 14 and 15, communicate with the passage 16. Metal heating pipes 19, which likewise have their ends welded or otherwise secured to the headers 14 and 15, extend in parallelism with and in close proximity to the pipes 18 and are preferably located slightly in advance of the pipes 18. Desirably solid or tubular bars of heat-conducting metal 20 are interposed between the pipes 18 and 19 for the purpose of conducting heat from the heating pipes 19 to the steam delivery pipes 18.

The lower portions of the steam delivery pipes 18 are provided with suitable outlets, such as perforations 21, so located as to project currents of steam in a downwardly and in a streamlined path upon the traveling sheet 1 of paperboard the full width thereof. Preferably, as illustrated in the drawings, the perforations 21 in the steam delivery pipes 20 are so located as to project the steam downwardly along the heating bars 20 against the surface of the steam pipes 20 in such manner as to cause the currents of air to be directed in the streamlined path, as above described.

The exit opening 22 through which the web of paperboard 1 passes from the steam chamber 6 desirably is somewhat larger than the inlet opening 23 through which the paperboard enters the steam chamber so that the steam will follow the web of paperboard as it passes toward the complementary rolls 7 and 8 the blades of which press and indent the parallel lines in the surface zone of the sheet.

Steam may be supplied to the steam delivery pipes and to the heating pipes in the steam cham-

ber from the same source, such for example as from a steam boiler which generates and maintains the steam at approximately one hundred twenty-five pounds per square inch. In such case, however, suitable means are provided for reducing the pressure of the steam supplied to the steam delivery pipes and for eliminating the water condensation which is produced by the reduction in steam pressure.

In the apparatus illustrated herein steam is supplied from the boiler through a pipe 24 to a reducing valve 25 where its pressure is reduced, for example, to five pounds pressure, and passes thence through a pipe 26 through a suitable eliminator 27, thence through a pipe 28 having therein a shut-off valve 29 to the passage 16 which communicates with the steam delivery pipes 18. Such steam as is not projected from the delivery pipes and any water condensation thereof passing from the opposite end of the passage 16 may be discharged through a valved pipe 30.

The high pressure steam for the heating pipes 19 is supplied through a suitable pipe 31 having a valve 32 to the passage 17 in the header, preferably at the opposite end from that in which low pressure steam is supplied, and passes therefrom into the several heating pipes 19 and is discharged from the opposite end of the header which is adjacent to the inlet for the low pressure steam through a pipe 33 to a suitable steam trap 34 and thence through a return pipe 35 to the boiler.

It will be understood that the respective conduits 16 and 17 of each of the headers are similarly supplied with low pressure and high pressure steam.

By reason of the construction above described the web of fabric is continuously enveloped in the steam as it passes through the steam chamber. The low pressure steam which is supplied to the passage 6 is projected downwardly in a streamlined path upon the upper surface which contains the more dense fibres of the sheet, thereby causing the surface zone to absorb vaporized moisture from the steam. Condensation in the flowing stream of steam is prevented by the contact of the steam with the heating pipes and also with the heat radiating bars which connect the heating and steam delivery pipes. The heat also supplied by the heating pipes serves to prevent condensation of any considerable amount of moisture within the heating chamber, thereby avoiding unequal absorption of moisture by any portion of the sheet as it passes through the steam chamber.

By reason of the present invention the paper-board sheet is properly conditioned to be acted upon by the rolls which impress thin lines into the surface zone of the sheet having the thicker fibre, so that the fibres will not be severed or broken by the action of the thin blades to impress the lines in the sheet, so that when the sheet is severed into sections of suitable length and dried the thickened or outer surface zone of the sheet may be bent into tubular form without rupturing the fibres of the surface zone.

The action of the steam upon the printed portions of the sheet serves not only to cause the ink to penetrate the surface zone of the sheet but also dries it sufficiently so that when the printed lines are impressed into the sheet the ink will not be removed by the blades of the impression roller. By thus impressing into the sheet printed lines of a selected color which will be descriptive of the contents of the container all danger of such

obliteration as will obscure the lines is prevented so that the person using the container may readily identify the proper container or a particular product when packing the same, and also readily identify it from any position of observation after the container has been loaded or packed, and even though the container has been subjected to such usage as would remove or destroy such features of the design as are printed upon the smooth surfaces of the sheet.

Having thus described the invention, what is claimed as new, and desired to be secured by Letters Patent is:

1. Steps in the method of forming collapsible bodies for knockdown containers from a flat sheet of suitable fibreboard which comprises moving the sheet lengthwise, projecting upon one surface of said sheet throughout its width a streamline current of low pressure steam flowing in the direction of movement of the sheet, supplying dry heat at a higher temperature directly and locally to said flowing stream of low pressure steam to superheat it and prevent condensation thereof and to cause uniform impregnation by dry steam of the surface zone of the sheet upon which said current is projected and simultaneously indenting suitably spaced transverse thin parallel lines into the surface of said sheet within and while subjected to said flowing current of steam thereby preventing breakage of the fibres of the surface zone of said sheet and rendering it flexible when dry.

2. Steps in the method of forming collapsible bodies for knockdown containers from a flat sheet of suitable fibreboard which comprises moving the sheet lengthwise through a surrounding volume of steam, projecting upon one surface of said sheet throughout its width a uniform streamline current of low pressure steam flowing in the direction of movement of the sheet, supplying dry heat at a higher temperature directly and locally to said flowing stream of low pressure steam throughout its width to prevent condensation thereof and to cause greater uniform impregnation by dry steam of the surface zone upon which said current is projected than the impregnation of the opposite side of said sheet by absorption of moisture from said surrounding volume of steam and simultaneously indenting suitably spaced transverse thin parallel lines into the surface zone of said sheet within and while subjected to said flowing current of steam, thereby preventing breakage of the fibres of said surface zone and rendering it flexible when dry.

3. Steps in the method of forming collapsible bodies for knockdown containers from a flat sheet of suitable fibreboard which comprises moving the sheet lengthwise through a surrounding volume of steam, projecting upon one surface of said sheet throughout its width a plurality of uniform streamline currents of low pressure steam flowing in the direction of movements of said sheet and following said sheet when merging thereupon, supplying dry heat at a higher temperature directly and locally to each flowing stream of low pressure steam throughout its width to prevent condensation thereof and to cause uniform greater impregnation by dry steam of the surface zone upon which said currents are projected than the impregnation of the opposite side of said sheet by absorption of moisture from said surrounding volume of steam, and simultaneously indenting suitably spaced transverse parallel lines in the surface of said sheet within

and while subjected to the merged streamline currents of steam.

4. The method of forming collapsible bodies for tubular knockdown containers from a sheet of suitable paperboard which comprises causing the sheet of paperboard progressively to pass lengthwise through a surrounding volume of steam thereby to moisten and soften the surface zones of the sheet with moisture and render them pliable, then indenting into successive sections of the moistened sheet without breaking the fibres thereof thin parallel lines with the spacing of the lines in each section gradually increasing in width through one-quarter of said section, then correspondingly decreasing in width in the next quarter section, then correspondingly increasing in width in the next quarter section, and correspondingly decreasing in width in the last quarter section, severing the successive sections from the sheet, and securing together in overlapped relation the narrow end panels of the sections defined by the lines adjacent the respective ends of the section.

5. The method of forming cylindrical collapsible bodies for tubular knockdown containers for flavored ice cream from a sheet of paperboard and providing non-obliterable means for identifying the flavor or character of the contents of the container which comprises printing a design upon the sheet including suitably spaced narrow parallel transverse lines of a predetermined color adapted to identify the contents of the container, progressively passing the printed sheet lengthwise through a surrounding volume of steam thereby to soften the surface zones of the sheet and render them pliable, then indenting portions of said printed lines into the moistened sheet, thereby to render the sheet flexible when dry and to prevent the printing of the indented portions of the line from obliteration, cutting the sheets into sections of suitable length and securing together overlapped end portions of each section to provide a liquid-tight joint.

6. The method of forming collapsible bodies for tubular knockdown containers from a sheet of suitable paperboard which comprises passing the sheet lengthwise through a surrounding volume of substantially dry steam, causing a current of said steam to move in a streamlined path in the direction of movement of the sheet and in contact with the surface zone of the sheet, supplying heat to said current of steam to prevent premature condensation prior to its contact with the sheet, thereby to moisten and soften said surface zone and render it pliable, then indenting into successive sections of the moistened sheet without breaking the fibres thereof thin parallel lines with the spacing of the lines in each section gradually increasing in width through one-quarter of said section, then correspondingly decreasing in width in the next quarter section, then correspondingly increasing in width in the next quarter section, and correspondingly decreasing in width in the last quarter section, severing the successive sections from the sheet, and securing together in overlapped relation the narrow end panels of the sections defined by the lines adjacent the respective ends of the section.

7. Apparatus for use in forming collapsible bodies for tubular containers from a sheet of paperboard comprising means for moving the sheet of paperboard horizontally lengthwise, an insulated steam chamber enclosing a predetermined portion of the moving sheet having entrance and exit apertures therefor, metal steam delivery pipes extending horizontally across said

chamber spaced from the sheet and having means for projecting a substantially uniform current of steam throughout the width of said sheet in a streamlined path against the surface of said sheet

5 in the direction of movement of the sheet, means for supplying low pressure steam to said steam delivery pipes, means for preheating said low pressure steam to render it dry when projected from said delivery pipes, metal heating pipes extending transversely across said steam chamber in parallelism with and in proximity to said steam delivery pipes so located in the path of the current of steam projected from said steam delivery pipes to aid in streamlining the current of steam along the moving sheet, and means for supplying high pressure steam to said heating pipes thereby to superheat the streamlined current of steam and prevent condensation thereof before impingement of the steam upon the sheet.

20 8. Apparatus for use in forming collapsible bodies for tubular containers for ice cream from a sheet of paperboard having non-obliterable means for identifying the contents of the containers comprising means for printing upon the 25 surface of the sheet a design comprising parallel suitably spaced lines of the color adapted to identify the contents of the container, means for passing the printed sheet lengthwise through an insulated chamber, enclosing a predetermined portion of the moving sheet, having an entrance and exit opening, steam delivery pipes extending horizontally across said chamber spaced from said sheet having means for projecting a substantially uniform current of steam from said steam 30 delivery pipes throughout the width of said sheet is a streamlined path against the surface of the sheet in the direction of movement of the sheet, means for supplying low pressure dry steam to said steam pipe, means for heating the currents 35 of steam in said chamber, and means located in proximity to the exit from said chamber for indenting the printed lines into the moistened surface of said sheet.

9. Apparatus for use in forming collapsible 40 bodies for tubular containers from a flat sheet of suitable fibreboard comprising a steam chamber having at its opposite ends parallel narrow entrance and exit slots for the fibreboard sheet, means for passing the sheet lengthwise there- 45 through, means within said chamber for project- 50 ing a streamline current of low pressure steam upon the surface of said sheet throughout its width in a streamline path in the direction of movement of the sheet to impregnate the fibres 55 of the surface zone thereof with moisture in vaporous form and to cause said current of steam to follow said surface from and beyond the exit slot of said chamber, and means located within the field of said following current 60 of steam for indenting transverse thin lines into said surface zone during the continued impregnation of moisture therein from said following steam current.

10. Apparatus for use in forming collapsible 65 bodies for tubular containers from a flat sheet of suitable fibreboard comprising a steam chamber having at its opposite ends parallel narrow entrance and exit slots for the fibreboard sheet, means for passing the sheet lengthwise there- 70 through, means within said chamber for project- 75 ing a streamline current of low pressure steam upon the surface of said sheet throughout its width in a streamline path in the direction of movement of the sheet to impregnate the fibres of the surface zone thereof with moisture in vapor-

ous form and to cause said current of steam to follow said surface from and beyond the exit slot of said chamber, means located within the field of said following current of steam for indenting transverse thin lines into said surface zone during the continued impregnation of moisture therein from said following steam current, and means within said chamber for supplying directly and locally to the current of low pressure steam throughout its width dry heat at a higher temperature to superheat said current and to prevent condensation of said low pressure steam, thereby insuring impregnation of said surface zone uniformly by vaporized moisture.

11. Apparatus for use in forming collapsible bodies for tubular containers from a flat sheet of suitable fibreboard comprising a steam chamber having at its opposite ends parallel narrow entrance and exit slots for the fibreboard sheet, means for passing the sheet lengthwise therethrough, a plurality of steam delivery pipes extending transversely across said chamber spaced from said moving sheet and from each other having means for projecting successively uniform currents of low pressure dry steam in streamline paths throughout the width of said sheet against one surface of the sheet in the direction of movement of the sheet to moisten said sheet and to cause the merging currents to follow said surface from and beyond the exit slot in said chamber, means for supplying dry low pressure steam to said steam delivery pipes, transverse heat-radiating pipes for high pressure steam intermediate of the respective steam delivery pipes and said sheet, metal bars welded to and connecting said steam delivery pipes and said heat radiating pipes throughout their length presenting heat radiating surfaces so positioned in the path of the respective currents as directly to heat said currents and aid in directing them in streamline paths, means for supplying high pressure steam to said heat radiating pipes, and means located in the field of the current of steam following the sheet from said exit slot for indenting transverse parallel thin lines into said moving sheet within and while subjected to the moisture of said following steam current.

12. Apparatus for use in forming collapsible bodies for tubular containers from a flat sheet of suitable fibreboard comprising a steam chamber having at its opposite ends parallel narrow entrance and exit slots for the fibreboard sheet, means for passing the sheet lengthwise therethrough, a plurality of steam delivery pipes extending transversely across said chamber spaced from said moving sheet and from each other having means for projecting successively uniform currents of low pressure dry steam in streamline paths throughout the width of said sheet against one surface of the sheet in the direction of move-

ment of the sheet to moisten said sheet and to cause the merging currents to follow said surface from and beyond the exit slot in said chamber, means for supplying dry low pressure steam to said steam delivery pipes, transverse heat-radiating pipes for high pressure steam intermediate of the respective steam delivery pipes and said sheet, metal bars welded to and connecting said steam delivery pipes and said heat radiating pipes throughout their length presenting heat radiating surfaces so positioned in the path of the respective currents as directly to heat said currents and aid in directing them in streamline paths, means for supplying high pressure steam to said heat radiating pipes, and means located in the field of the current of steam following the sheet from said exit slot for indenting transverse parallel thin lines into said moving sheet within and while subjected to the moisture of said following steam current.

13. Apparatus for use in forming collapsible bodies for tubular containers from a flat sheet of suitable fibreboard comprising a steam chamber having at its opposite ends parallel narrow entrance and exit slots for the sheet, means for passing the sheet lengthwise therethrough, suitably spaced parallel headers for low and high pressure steam within said chamber extending lengthwise thereof, spaced transverse steam delivery pipes communicating at their ends with the headers for the low pressure steam spaced from the path of the sheet and provided with apertures for projecting said low pressure steam upon the upper surface of the sheet throughout its width in a streamline path in the direction of movement of said sheet, means for supplying low pressure steam to the low pressure steam headers adjacent to the exit slot of said chamber, means for delivering said low pressure steam freely from the opposite end of said header, means for eliminating condensed moisture from said low pressure steam before its entrance into said headers, parallel transverse heat radiating pipes communicating at their ends with said high pressure headers located adjacent to and in parallelism with said steam delivery pipes and intermediate of said steam delivery pipes and said sheet so positioned as to aid in deflecting the respective currents of low pressure steam in said streamline path, and means for supplying high pressure steam to said high pressure steam headers adjacent to the inlet slot of said chamber, and means for freely discharging said high pressure steam from the opposite ends of said headers.

HARRY A. WANSKER.
